UNITED STATES PATENT OFFICE.

MAXEY JACKSON, OF TOPPENISH, WASHINGTON.

RAIL-JOINT.

1,206,710.

Specification of Letters Patent. Patented Nov. 28, 1916.

Application filed March 16, 1916. Serial No. 84,677.

To all whom it may concern:

Be it known that I, MAXEY JACKSON, a citizen of the United States of America, residing at Toppenish, in the county of 5 Yakima and State of Washington, have invented certain new and useful Improvements in Rail-Joints, of which the following is a specification.

This invention relates to railway rails, 10 and more particularly to the joints and means for securing the abutting ends thereof together.

One of the objects of the invention is to construct a rail joint that will distribute the 15 strain brought to bear thereon, due to a train passing thereover.

Another object of the invention is to construct the ends of rails, whereby two abutting ends of rails will interlock and absolutely prevent lateral movement of one rail 20 with relation to the other.

Another object of the invention is to connect the abutting ends of rails to shift the load of a train passing thereover, from one 25 rail to its adjacent rail, before the load leaves the first mentioned rail.

A still further object of the invention is to provide a rail joint of this character which will be strong, durable and inexpensive 30 to construct, efficient and reliable in operation and well adapted to the purpose for which it is designed.

In the drawings: Figure 1 is a perspective view of the end section of two abutting 35 rails. Fig. 2 is a top plan view of the terminals of rails shown separated. Fig. 3 is an end view constructed in accordance with my invention. Fig. 4 is an enlarged side elevation of the end of one of the rails.

Referring now to the drawing, I have 40 shown two abutting rail sections 5 and 6, each of which comprises the usual base 5' having an integral web 6', which terminates in a head or tread section 7. In the construction 45 of the present rail joint, the tread 7 of the rail 6 is cut at an angle of 45° with respect to the edge of the rail, and said cut extends to the bottom of the tread or to a point where the web 6' merges into the tread 7.

At this point a semi-circular cut out portion 11 is provided, said cut out portion extending transversely of the web, and the walls adjacent the cut out portion provide a shoulder 9, on one side of the web 6' and 50 a shoulder 9² on the opposite side lying in a plane above the shoulder 9 for a purpose

to be hereinafter more particularly described.

Starting at a point adjacent the semi-circular cut-out portions and continuing 60 through the webs 6' and base 5' of the rail 6, the rail is cut at an angle as at 10, the angle being preferably 45° and in the opposite direction from the angle at which the tread 7 is cut, thereby presenting oppositely beveled walls, which coöperate with the coinciding walls of the adjacent end of a rail 5, with the result that, due to the opposed angles of the adjacent rail ends, 65 the rails are interlocked, the joint thus producing strong resistance to lateral motion 70 of the rail terminals.

The end of the rail 5 is cut as at 10', through the thickness of the tread, this cut also extending at an angle with relation to 75 the edge of the rail and at an angle directly parallel to the edge 8 of the adjacent rail end 6. The end of this section 5 is also cut through the web and base on the same angle, and directly opposite the angle 80 on which the tread portion 10' is cut. A semi-circular cut-out portion 11' is also formed in the rail 5, at the point where the web 12' merges into the tread 10', the walls adjacent said cut-out portion 10' also forming 85 a shoulder 12' on one side of the rail and a shoulder 12² on the opposite side, the shoulder 12² lying in a plane above the shoulder 12'.

In assembling the device, the abutting 90 ends of the rail sections 5 and 6, are brought together, with the result that the ends interlock, and form a perfect splice joint, avoiding direct vertical alinement of the joint, whereby the joint is greatly strengthened. 95 A suitable wedge or bolt, not shown, may be inserted through the opposing semi-circular cut-outs for more securely interlocking the rail ends together against upward movement, said wedge or bolt passing 100 through the fish plates or being housed thereby.

It might further be stated that the shoulders 9 and 12' form seats for a portion of the adjacent rail brought to bear on one rail, 105 throughout the adjacent rail section. After the ends of the rail sections are brought together, the usual fish plate sections not shown are positioned adjacent the sides of 110 the rails, and clamped in such position by bolts or similar securing means.

It is to be understood that the details may

be modified without departing from the spirit of my invention.

What I desire to claim is:

In a rail joint, rail sections having the tread portions thereof cut at an angle with relation to the edge thereof, the webs and bases thereof being cut at an angle in the opposite direction, each section having a semi-circular cut out portion in the web 10 thereof adjacent the tread, shoulders formed

by the semi-circular cut out portions and shoulders formed on the rail section on opposite sides from the shoulders formed by the semi-circular cut out portions, the shoulders formed by the semi-circular cut out 15 portions lying in a plane above the shoulders formed on the opposite sides of the respective rail sections.

In testimony whereof I affix my signature.
MAXEY JACKSON.
